(57) **CLAIM**

The ornamental design for the hair curler, as shown and described.

DESCRIPTION

FIG. 1 is a perspective view of the hair curler showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom plan view thereof.

FIG. 8 is a perspective view thereof; showing the hair curler in an environment of use; and,

FIG. 9 is another perspective view thereof, showing the hair curler in an alternate environment of use.

The broken lines illustrate the environment of the hair curler and form no part of the claimed design.
